US00D799268S

(12) **United States Design Patent** (10) Patent No.: **US D799,268 S**
(45) Date of Patent: **** Oct. 10, 2017**

(54) **BEVERAGE CONTAINER**

- (71) Applicant: **EMBER TECHNOLOGIES, INC.**,
Westlake Village, CA (US)
- (72) Inventors: **Martin Gschwandtl**, San Francisco,
CA (US); **Eric Fields**, San Francisco,
CA (US); **Stephen Steger**, San
Francisco, CA (US); **Christopher Kuh**,
San Francisco, CA (US); **Robert
Brunner**, San Francisco, CA (US)
- (73) Assignee: **EMBER TECHNOLOGIES, INC.**,
WestLake Village, CA (US)
- (**) Term: **15 Years**
- (21) Appl. No.: **29/561,688**
- (22) Filed: **Apr. 19, 2016**
